The ornamental design for a foldable visiting card, as shown and described.

DESCRIPTION

FIG. 1 is a top plan view of the foldable visiting card showing my new design, with the card shown in an unfolded condition; FIG. 2 is a left end elevational view thereof; FIG. 3 is a rear elevational view thereof; FIG. 4 is a view right end elevational thereof; FIG. 5 is a front elevational view thereof; FIG. 6 is a bottom plan view thereof; FIG. 7 is a top plan view of the visiting card shown in FIG. 1, with the card shown in a partially folded condition; and, FIG. 8 is a top plan view of the foldable visiting card shown in FIG. 1, with the card shown in a fully folded condition. The broken lines in FIGS. 1, 6, and 7 merely show the locations where the card is folded as shown in FIGS. 7 and 8 and form no part of the claimed design.
